ATTORNEY.

UNITED STATES PATENT OFFICE

PAUL CHAUMIER, OF DALLAS, TEXAS

HAIR WAVING DEVICE

Application filed January 30, 1931. Serial No. 512,353.

This invention relates to hair dressing equipment and it has particular reference to a device arranged to be fitted over the head, whereby the hair may be waved, with but little effort on the part of the subject or operator and the principal object of the invention resides in the provision of a hair waving device, adapted for use by the individual or by operators in beauty parlors and its simplicity and ease of operation is such as to enable an individual to wave her own hair without assistance, except perhaps in extreme cases.

Another object of the invention resides in the provision of a device of the character specified having a series of spaced, independently movable combs or hair engaging elements, the said combs being accessibly disposed to enable the operator to bring about the desired undulation in the hair.

Still another object of the invention resides in a device for waving the hair without the aid of additional instruments or accessories and is of such form as to reach below the ears whereby the hair on the crown as well as on the neck may be treated with the same degree of satisfaction. Moreover, the invention is so constructed that the combs therein may be adjusted to accord with individual types and styles of hair dressing, that is to say, whether the hair is parted in the middle or on the sides, or in the effect of a pompadour.

Broadly, the invention comprehends the provision of a hair waving device wherein movable combs, in spaced superimposed relationship engage the hair so that when they are operated, they will set the hair in waves of any desired depth, characteristic of the well known finger wave. In addition to this, the invention, being constructed of light material, conforms to the head of the subject and is not uncomfortable, which feature enables the subject to wear the device until such time as the hair has become set, whereupon the device may be removed and the hair combed out as is customary with the conventional type of finger wave.

With the foregoing objects as paramount, the invention has particular reference to its

salient features of construction and arrangement of parts all of which will become manifest as the description proceeds, taken in connection with the accompanying drawings, wherein:

Figure 1 is a perspective view, showing the preferred embodiment of the invention.

Figure 2 shows the invention operatively applied.

Figure 3 is a plan view of the invention, showing the manner in which the same is applied, as in Figure 2.

Figure 4 is a fragmentary view of one form in which the combs are movably secured to the frame.

Figure 5 is a modified form of Figure 4.

Figure 6 is a fragmentary view of the comb per se shown in Figure 5, and

Figure 7 shows a transverse sectional view of the comb shown in Figures 4 and 6.

Continuing more in detail, it may be stated for the sake of clarity that the invention is primarily adapted to provide a much needed substitute for the well known type of finger wave, whereby the individual may wave her own hair at home without assistance, primarily in view of the expense of having this work done. Not only is the invention very useful in this connection but it is found likewise practical to employ the same for resetting permanent waves. It is also pointed out that while practical for home use, the improved hair waving device may be employed equally as effectively in beauty shops and in other places where the art is practiced.

Accordingly, 1 designates a thin band of flexible material, having the characteristics of steel or hard rubber, although the former has been adopted in view of the durability thereof. To the ends of this flexed strip or band 1 is connected a substantially U-shaped member 2, which member, when the device is applied to the head of the subject as shown in Figure 2, passes about the nape of the neck. The device thus fits the head of the subject in very much the same manner as a cap and as a reinforcing means, a band 3 is provided, having one end affixed at the bend in the member 2 and extending upwardly, where it bows over the crown of the head, terminating in an

adjustable connection at 14, to the band 1.

The fact that this connection at 4 is adjustable enables the device to be conformably fitted to the head of the subject, whereby the 5 combs or hair engaging elements to be presently described, may likewise conformably engage the scalp and thus insure uniformity of pull upon the hair, without displacement which will result in the production of an irregular wave.

It will be observed that longitudinal slots 5 are provided in both the band 1 and the reinforcing band 3, centrally connected to the said band 1. These slots are arranged to receive bolts 6 having comb engaging elements 7. In this connection, it is pointed out that the structure shown in Figure 5 embodies a series of slotted ferrules or tubes 8, which extend in a circular form from one side of the 20 band 1 to the other. These tubes being hollow, the ribs 9, either integral or connected with the combs 10, are capable of sliding movement in the said tubes or ferrules 9.

Modified forms of the arrangement just described are shown in Figures 4, 5 and 6, in Figure 4, the rib 9, instead of passing through a ferrule extending completely around the back of the head, extends through a short tube, bearing the same reference character, while the remainder of the cone rib 9 is exposed. This manner of arrangement is found to minimize friction and permit the combs 10, or rather the ribs 9 bearing the combs to be more readily moved.

With further reference to Figure 1, particular notice will be taken of the fact that the combs are severally disposed at an incline in the frame. This particularly adjusted position of the combs is such as to produce the waves shown in Figures 2 and 3. In other words, angular disposition of the several circular combs is concentric with the part in the hair, exposed by two normally stationary and straight combs 11. The fact 45 that these combs are stationary, enables the uppermost of the circular combs to be moved in a reverse direction to that of the short comb 12 at the extreme crown. The concentric undulations produced by alternate movement of the combs in different directions begins at the part in the hair and continues around the head in such relationship to a point below the ears at an angle relative to the crown. It has been previously stated 50 however, that the slots 5 in the members 1 and 3 enable the circular combs to be adjusted to a reverse angle in cases where the coiffure demands that the undulations in the hair be concentric relative to a part on the left side 55 of the head rather than the right side as shown. Moreover, adjustments of the circular combs may be made to produce waves concentric with the crown of the head. It is all important however, in order to successfully 60 produce a desirable wave, that the circular

combs continue from the crown to the nape of the neck, as shown in Figure 2. In this manner, either the individual or an assistant may wave the hair uniformly over the entire area of the scalp and the hair that might escape the lowermost comb may be readily turned up to conform with the undulations put into the hair by the device.

While it is not particularly necessary, it is at least desirable to affix the device on the head in such position that it will not become easily displaced. For this purpose, a strap 13 connects to the ends of the band 1 and passes under the chin of the subject. This arrangement will hold the device securely while the combs 10 are being moved to set the hair as shown. In operation, the device shown in Figure 1 is first adjusted to the head of the subject by first loosening the nuts 14 on the screws or belts 6, which allows for free and unrestricted movement at the point 4, forming the connection between the band 3 and the band 1. This having been done, the screw 14 holding the comb mountings in rigid position relative to the frame is loosened to allow the mountings to be adjusted to suit the desired coiffure or in other words, that the combs may be so positioned relative to the part, using the stationary combs 11 as a point from which to determine the proper adjustment of the combs 10.

The device is placed upon the head of the subject in the manner shown in Figure 2, after having tightened the nuts 14 to secure the comb mountings 8. The strap 13 is adjusted under the chin of the subject.

It is understood of course, that any suitable wave fluid is first applied to the hair before the device is arranged upon the head of the subject and the hair is combed according to the usual methods employed in giving so called finger waves.

After the necessary preparations described, the short comb 12 is pulled forward, the nearest of the stationary combs 11 resisting the movements of said comb 12, causing the hair to be pulled forward toward the forehead, in the manner shown in Figure 3. After adjusting this comb, the uppermost of the circular combs is moved against the resistance of the outer of the stationary combs 11, to impart a pull upon the hair out of the influence of the combs 11 and 12. The next succeeding comb 10 is moved in the opposite direction, while the third circular comb is moved in the same direction as the first or that comb nearest the crown of the head. This operation continues until the desired results are obtained, it being pointed out that the lowermost comb is shorter than the other combs of the assembly.

The fact that the ribs 9 protrude a substantial distance from the fixed elements 8, in which the combs 10 are moved, enables the individual to very effectively make the afore-

said adjustments very effectively without assistance.

The device described, after the adjustments are made in accordance with the foregoing is allowed to remain in operative position until the hair has had the opportunity to become thoroughly dry, whereupon the strap 13 is released and the device is removed from the head, after which the hair may be given the final touches, such for instance as setting loose strands to accord with the wave produced by the invention.

The invention has been described with great particularity, and it is understood that it is not intended that the same shall be limited to the specific arrangement and construction of parts and that certain changes and modifications may be resorted to from time to time as may fall within the scope and meaning of the appended claims.

1. A hair waving device including a frame having a series of independently movable combs and a pair of stationary combs, the said independently movable combs being arranged for movement in concentric relationship with said stationary combs.

2. A hair waving apparatus including a frame comprised of an expandable inverted U-shaped fore piece, the ends of which terminate operatively below the chin of the wearer, a pair of normally stationary combs and a series of circular combs secured to said fore piece for endwise movement independent and relatively spaced from the top of said frame to the lowermost portion thereof.

3. A device of the character described for use in hair waving including a frame comprised of an inverted U-shaped fore piece, a series of substantially circular hair engaging members capable of independent sliding movement and means for adjusting the positions of said hair engaging elements independently in said frame.

4. A device of the character described including an open frame, arranged to be conformably fitted to the head, the lower edge of which terminates below the hair line and having a frontal piece defining the face and a series of independently slidably and concentrically spaced circular combs arranged for endwise and lateral adjustment relative to said frontal piece.

5. A device of the character described including a frame arranged to be fitted upon the head, comprised of a circular element embracing the neck at a point below the hair line and a frontal piece embracing the face and having its ends connected to said circular element, a reinforcing strip engaging said circular element and having an end adjustably connected to said frontal piece and a series of circular toothed elements connected for independent endwise sliding movement in said frame.

6. A device of the character described for

use in hair waving including a flexible frame arranged to be fixed upon the head, comprised of a circular element embracing the neck and terminating at a point below the ears, a frontal piece whose ends are connected to the ends of said circular element, circular toothed elements having their ends slidably connected at spaced points on said frontal piece and formed to circularly engage the head at spaced intervals from the crown to the hair line.

In testimony whereof I affix my signature.

PAUL CHAUMIER.
